UNITED STATES PATENT OFFICE.

SILAS LAND, OF PHILADELPHIA, PENNSYLVANIA.

IMPROVEMENT IN SELF-ACTING EYELET-BATTENS.

Specification forming part of Letters Patent No. **64,016**, dated April 23, 1867.

To all whom it may concern:

Be it known that I, SILAS LAND, of the city and county of Philadelphia, and State of Pennsylvania, have invented a new and useful Improvement in Self-Acting Eyelet-Battens; and I do hereby declare that the following is a full and exact description thereof, reference being had to the accompanying drawings, and to the letters of reference marked thereon.

The nature of my invention consists in confining battens to the backs of signs, or other boards, by means of the use of slotted eyelets constructed of cast-iron or other suitable metal, which receive the heads of the screws used for fastening the battens. The slots in the eyelets allow the screw-heads to slide as the board shrinks, and incline toward the joint of the board, as will be seen by the following description.

In the accompanying drawings, Figure 1 is a plan of a board with the improvement attached to the battens. Fig. 2 is an edge view of the same.

A is a board, which has a joint, *a*. B B are the battens, on the outer surface of which are placed eyelets C, through the slots *b* of which the confining-screws D pass. The slots have

beveled sides to receive the heads of the screws.

The eyelets operate as follows: When the board shrinks, the slots in the eyelets allow the heads of the screws to change their position in accommodation thereto, and thus prevent the drawing of the two pieces *i i* apart, as occurs in the usual mode of battening. Besides preventing the breaking of the joint, the screws being allowed to change their position relatively toward the joint, the improvement acts auxiliarily to the battens in preventing the warping of the board.

What I claim as my invention, and desire to secure by Letters Patent, is—

The combination of the slotted eyelets C with battens B, arranged and operating in relation to signs or other boards, substantially in the manner described, and for the purposes specified.

In testimony whereof I have hereunto set my hand and affixed my seal this 5th day of February, 1867.

SILAS LAND. [L. S.]
